UNITED STATES PATENT OFFICE.

FRANZ RAUCHWETTER, DECEASED, LATE OF BERLIN-FRIEDENAU, GERMANY; BY ANNA RAUCHWETTER, GEB. BÖHME, ADMINISTRATRIX, OF BERLIN-FRIEDENAU, GERMANY; ALFRED FLATER, PRESENT ADMINISTRATOR OF SAID FRANZ RAUCHWETTER, DECEASED.

PRINTING DEVICE FOR CALCULATING MACHINES.

Application filed May 19, 1921. Serial No. 471,017.

To all whom it may concern:

Be it known that FRANZ RAUCHWETTER, deceased, late a citizen of the German Republic, and residing at Berlin-Friedenau, 5 Germany, invented certain new and useful Improvements in Printing Devices for Calculating Machines, of which the following is a specification.

This invention refers to a printing device 10 for calculating machines, especially for calculating machines operated by keys the object of the device being to print any desired single number as may be set on the key board, as also, by means of a simple change-over device, to print the sum total, of the 15 counting mechanism; further, by a simple operation of a key the entire printing mechanism may be disconnected, and the calculating machine may be used as any 20 ordinary machine. Moreover the new printing device has an arrangement by means of which groups of figures may be printed. One part of the printing device, e. g. the left hand side, may print one group of figures, whilst the second part of the printing 25 device prints another group.

The characteristic of the new printing device consists in the peculiar double and at the same time releasing advance control 30 of stops limiting the travel of the printing types, combined with the uniform operation of the types, in such a manner that corresponding to the advance control, either from the keys or from the counting mechanism, for the printing of sums set upon 35 the key board and added together by the counting mechanism, (i. e. the sum total), the travel of the type levers is limited. At the same time, if printing is to be done 40 from the keys, the advance control from the counting mechanism is switched out, and vice versa, if printing is to be done from the counting mechanism, the advance control from the keys is shoved aside.

45 It is, moreover, typical, that the driving gear of the printing device may be disconnected completely, inasmuch as the rocker levers operating the printing device are connected to the main driving shaft by 50 means of a peculiar lever-coupling which may be cut in or out. In order to print the sum total in a different color from the in-

dividual sums it is essential that the type ribbon, subdivided in two colours, be interlocked with the keys or with the counting 55 mechanism of the printing gear respectively in such a manner that it may be raised into different positions, corresponding to the colours of the type ribbon, by means of cam control, thereby using one colour for the 60 single printing, and another for the sum total.

Below, the printing device is to be described systematically according to the drawings.

Fig. 1 represents a view of the printing device and its control from the key board, certain parts of the driving gear such as the type lever drive, having been omitted.

Fig. 2 shows a plan view of the type lever 70 arrangement, and their connection to the lifting levers.

Figs. 3 and 3^a show a side view of one of the stops for the advance control of the type levers from the keys, in two different 75 positions.

Fig. 4 shows a view similar to Fig. 1, only with one of the keys pressed down, the other parts of the printing device being 80 in their respective positions, correspondingly.

Fig. 5 shows a view of the type lever connection from the counting mechanism, in the position of rest, also the driving gear from the main shaft of the machine.

Fig. 6 shows a view similar to Fig. 5, the drive, however being represented in the "engaged" position with the counting mechanism, and the hammer mechanism being 85 in the position, ready for printing.

Fig. 7 shows how the drive is disconnected for putting the printing works out of commission.

Figs. 8, 8^a, 9, 10, 11 are details of the hammer drive, and of the reciprocal coupling 95 between the hammers for printing the ciphers.

Fig. 12 shows a plan view of the arrangement for limiting the travel of the number disks, preventing them from moving beyond the zero position during printing.

Fig. 13 shows the uncoupling of the stop controlled in advance by the keys and by

the segment driving the counting mechanism for the printing of the totals.

Figs. 14 and 14^{a-b} represent a second method of design of the printing hammers and their continuous coupling, one with the other, acting towards the right, for the purpose of printing the ciphers.

The object is to set in advance, the type levers (1) by the keys (2), for printing a number set upon the key board, or by the counting mechanism (3), for printing the totals, so that the impression may be made by releasing the hammer. The adjustment of the type levers (1) is effected by means of the keys (2), as also by the counting mechanism (3), through an advance control, limiting the distance through which the operating lever travels in accordance with the advance control. This is accomplished by the keys (2), as shown on Figs. 1 and 4, inasmuch as a slide rod 2' is moved, corresponding to the travel of the key, this rod, in turn, controlling a lever (5) with a stop (6), the lever (5) swinging round the trunnion (4). The stop (6) limits the travel of the double swinging lever (8), (8') with stepped segment (9) by the latter hitting the stop (6) with a certain step, thereby being prevented from further following the movement of the driving crank (10) coupled to it by the spiral spring (11). This means that the movement of the type lever (1) which is likewise coupled to the arm (8') by the lever (12) and the rod (13) is limited by the stop (6) in a manner, corresponding to the key which is pressed down. It should be noted that, when the machine is switched over for printing from the counting mechanism, the stop (6) on the arm (5) may be brought out of reach of the arms (8) of the double lever (8, 8'), by a lateral movement (Figs. 3 and 3^a), as will be described later.

It should also be noted that, naturally, the type levers are not arranged the same distance apart as the columns of the machine, but in the usual manner, as may be seen from Fig. 2, the lateral differences of the distances being equalized by leading the double levers (12) at an angle across.

The control of the type levers from the counting mechanism is shown in Figs. 5 and 6 in two different positions, Fig. 5 showing the "disengaged" position of the intermediate segment, the driving parts of the type levers having been omitted; Fig. 6 showing the mechanism in the "engaged" position, all details of the driving mechanism being represented. If it is desired to print from the counting mechanism, the sum key (14) Fig. 6 is pressed down. By means of the slide rod (15) the sum key (14) adjusts the rocker (17) swinging on the trunnion (16), in such a manner that its face (18) enters into the path of a roller (19) which is

mounted upon the double rocker (20) turning on a fixed pin (21). At the same time the step (22) of the lever (17) enters below the stop (23) on the toothed segment (24) so that this toothed segment is taken along when the lever (17) is switched over by the driving mechanism, i. e. the segment is raised and brought within reach of the disk of the counting mechanism (3) as shown in Fig. 6. During this upward movement the double lever (20) is likewise swung over by the face (18) of the lever (17), whereby the rest (25) is lifted up (Fig. 6), so that the stop (27) of the counter disk (3) which in Fig. 5 could clear the projection (28) of the rod (25), is now arrested by the projection (28), thereby limiting the movement of the counting mechanism. The lever (5) for the stop (6) to be controlled in advance by the keys is coupled,—by a double lever (30) turning on the trunnion (30') as shown on Figs. 6 and 13—to the toothed segment (24) through the intermediary of the double lever (29) in such a manner that lever (5) together with the stop (6) are moved laterally in the direction of the arrow on Fig. 13, i. e. out of reach of the toothed segment (9) so that the printing mechanism is now no longer under the influence of the keys.

It is evident that after this advance control has been effected, the lifting of the type lever is limited by the travel of the disk of the counting mechanism from the number thereon, to zero, the reason being that the type levers (1), checked by the guide rod (13), and double lever (12) with bell crank (8, 8') are now limited by the movement of the guide rod (31) corresponding to the travel of the toothed segment (24) and, therefore, of the counter disk (3).

The lever (10) for operating the type levers from the crank (32) of the machine is driven through the intermediary of guide rods (33, 33') of a rocker (35) swinging about a fixed trunnion (34), further the guide rod (36) and the lever (37). At the same time the roller (38) (comp. starting position Fig. 5) of the rocker (39) swinging about the fixed point (38') is controlled by the slide rod (33') with rear extension, in such a manner that, running up upon the inclined plane (40) of the sliding rod, this roller is raised, thereby raising the lever (17). By this lifting movement the rests for the stops of the counting mechanism are raised, together with the latter, in the "engaged" position and the toothed segments are brought into the "engaged" position with the gear wheels of the counting mechanism. At the same time the advance control for the stop of the key pressure is disconnected.

In order to be able to use the calculating

machine also with the printing device disconnected the following cut-out coupling between the driving gear and the counting mechanism has been provided for (comp. 5 Figs. 5, 6 and 7). As shown on Fig. 6 the lever (35) swinging round the trunnion (34) transmits the movement of the crank (32) upon the crank (10). When the pivot of this lever is no longer fixed, but able to 10 move freely, the transmission of the movement upon the lever (10) through the sliding rod (36) will cease. In the printing position of the counting mechanism the pivot (34) fixed by a lever (42) swinging on 15 a pivot (41), and carrying a pivotal point (34) for the lever (35) will rest against a projection (43) of a lever (46) swinging about a pivot (44). If however (46) is 20 swung round the pivot (44) so that the projection (43) is out of reach of the lever (42), as shown on Fig. 7, the lever (42) may oscillate freely round the pivot (42), so 25 that the cranking movement of the rod (36) is no longer transmitted upon the lever (10).

The movement of the lever (46) is produced by the sliding rod (47) from the double lever (48), the latter lever being moved by the release key (49) as shown on 30 Fig. 6, namely by sliding the rail (50) in the direction of the arrow marked on Fig. 6. After the type lever has been set, the impression is made by means of the hammer levers (51) which can turn on the pivots 35 (52) and which are under the influence of the springs (53) in such a way that, after releasing the catches (54), engaging in hooks (54') on the hammers, the advance-controlled type lever strikes the type ribbon and the printing paper. The peculiarity of this hammer drive is the release of 40 the locking hooks (54), and the consecutive mutual coupling of these hammers towards the right with the object of printing the ciphers, and also for printing groups of 45 ciphers. These locking hooks (54) are released by the driving spindle (55) in the following manner: After the driving spindle has travelled through a certain distance a 50 stop (56) is arrested by coming up against a stop (57) of a lever (58). This latter lever moves another lever (60) provided with a hooked projection, carrying it along by means of the cross bar (59). In this 55 manner the hooked lever is released. (Compare also Fig. 1 with reference to the connection of the hooked levers (54).)

In order, now to print the ciphers if a 60 number contains several ciphers, the hammers are coupled together continuously towards the right, so that when one hammer is struck, the ciphers to the right are printed. This is done in the following manner: each type lever is provided with a recess 65 (61) which when the type levers are in the

position of rest, is opposite a projection (62) of a double lever (64), swinging on a pivot (63), so that when this lever (64) with its projection (62) drops into the recess (61), it no longer carries the opposite arm of lever 70 (60), allowing the latter to drop, so that no uncoupling of the hooked levers (54) from the shackle (59) can take place. In the normal position all levers (64) are disengaged from the recesses (61) of the type levers. 75 However, after the type levers (1) have been set, the lever (64) is swung so far to the left, (after releasing the double lever (64)), that its projection (62) drops into the groove (61) of the corresponding type lever. 80 The tripping of the lever (65), so that it may be drawn inward, by a spring, in the direction of the arrow on Fig. 8, (compare also Fig. 8^a), is now effected by means of the locking lever (66), coupled to it by a 85 spring, and controlled by the cam (67) through the roller (68). If lever (66) is raised by the roller (68), (comp. Fig. 8^a) it clears the lever (65) which swings inward. When this happens, the projections (62) of all levers (64) to the left of the highest number drop into corresponding recesses of the type levers, whereas all levers (64) to the right of the highest number are 90 kept in the raised position by means of two right angle bends (69) and (69') extending in opposite directions from the horizontal arms (64') of the levers (64) and placed, the one a certain distance above the other, so that the upper bend (69') of a left hand lever, leaving a certain space between them. Into this clearance space between the levers a locking rod (70) engages in such a manner that, as long as one left hand lever is raised, (i. e., prevented from dropping into its corresponding recess in the type lever) 95 all other levers to the right of this lever are likewise kept in the raised position, the arms (69) of the right hand levers resting upon the faces of the locking rods (70). 100

If it is desired, however, to print groups of numbers, it is possible, corresponding to the number of figures in any one group, by disconnecting one of the coupling rods (70) to uncouple permanently a series of right hand levers, notwithstanding the connection of left hand type levers. This may be effected by pushing back the respective coupling rod (70) so that it engages a slot (71) of a rail (72) which can slide at right angles across, thereby placing the forward extremity of the rod (70) beyond the reach of the bends (69) and (69') of the levers (64). 115

The cocking of the hammers for printing is effected by the cam disk (67) already described, (compare Fig. 8, but more especially Fig. 6) in such a manner that a roller (73) of a rocker (74) embracing all the hammers, and swinging round the pivot (52) runs up upon the periphery of this cam 120

disk. The movement of the cam disk is effected by the guide rod (75) and the cam (76) from the driving shaft (77).

In order to print the sum total and the group totals in different colours the lifting rod (78) of the type ribbon is connected by the double lever (80) swinging on the pivot (79) in such a manner that when roller (81) runs upon the higher part of the curve, one part of the type ribbon is in the printing position, whereas upon the lower part of the curve the other part of the type ribbon is in a position for printing.

A second method of construction of the coupling of the printing hammers as shown in Figs. 14 and 14^a, for two positions of the hammers, Fig. 14 representing the "off," and Fig. 14^a the "printing" position. For this second design each type lever is provided, in place of the milled slot (61), with a pin (61'), by which a lever (85) swinging on a pivot (84) is pressed down in such a manner, that the rocker (59) is released, thereby rendering a tripping of the corresponding hammers impossible. This pressing down of the levers (85) takes place in the "zero" position of the type levers. In order, however, to release also those hammers placed to the right of a maximum number, and for printing the corresponding ciphers, despite the releasing of all levers (85), these latter are provided with swinging levers (87) which can turn on pivots (86). During this movement the front face of this lever pushes against a pin (84) of a left hand adjacent lever (85) so that when this adjacent lever on the left is switched, it carries the preceding lever (87), on the right, and all the following ones along with it, so that from the highest number on the left all levers (85) to the right are taken along, thereby also releasing all the printing hammers to the right.

In order, however, to print results in groups, as with the first type of construction, the printing mechanism may be subdivided into groups, by one lever (85) being released in that position in which the subdivision in groups is to take place, by a special rail (88) being released in that position in which the subdivision in groups is to take place, by a special rail (88) provided with notches. Whenever a notch of the rail (88) comes below the left arm of the lever (87), (compare especially Figs. 14 and 14^a), this lever is placed beyond the reach of the pin (84) of the adjacent position to the left, by the action of a spring (89).

Claims.

1. A printing device for calculating machines, comprising, in combination; a driving mechanism; a writing roller; type-bars adapted to be adjusted by means of said driving mechanism and being arranged in front of said roller; means for vertically

guiding said bars; a counting mechanism and cog-wheels forming members of this mechanism; toothed segments adapted to co-operate with said cog-wheels; a lever-mechanism adapted to couple said type-bars with said toothed segments; abutments forming members of the driving mechanism and being adapted to be adjusted from the keys of the machine; bell-crank levers having one arm extending over the associate abutment; stepped sectors attached to these arms and being adapted to co-operate with said abutments; a hammer-mechanism and type hammers forming members of this mechanism; a common axle for said hammers; a rocking bar arranged transversely with respect to said type-hammers and being adapted to release them; and means for transmitting motion from the machine shaft to said rocking bar.

2. A printing device for calculating machines, comprising, in combination a driving mechanism; a writing roller; type-bars adapted to be adjusted by means of said driving mechanism and being arranged in front of said roller; means for vertically guiding said bars; a counting mechanism and cog-wheels forming members of this mechanism; toothed segments adapted to co-operate with said cog-wheels; a lever-mechanism adapted to couple said type-bars with said toothed segments; abutments forming members of the driving mechanism and being adapted to be adjusted from the keys of the machine; bell-crank levers having one arm extending over the associate abutment; stepped sectors attached to these arms and being adapted to co-operate with said abutments; levers having the said abutments attached to them; bars connecting these levers with said keys; an axle carrying these levers and being so arranged in the driving mechanism as to be adapted to be laterally displaced in it; a hammer-mechanism and type hammers forming members of this mechanism; a common axle for said hammers; a rocking bar arranged transversely with respect to said type-hammers and being adapted to release them; and means for transmitting motion from the machine shaft to said rocking bar.

3. A printing device for calculating machines, comprising, in combination a driving mechanism; a writing roller; type-bars adapted to be adjusted by means of said driving mechanism and being arranged in front of said roller; means for vertically guiding said bars; a counting mechanism and cog-wheels forming members of this mechanism; toothed segments adapted to co-operate with said cog-wheels; a lever-mechanism adapted to couple said type-bars with said toothed segments; abutments forming members of the driving mechanism and being adapted to be adjusted from the

keys of the machine; bell-crank levers having one arm extending over the associate abutment; stepped sectors attached to these arms and being adapted to co-operate with 5 said abutments; a switching key; a rail forming a member of the driving mechanism and being adapted to be lifted by means of this key; a lever-mechanism connecting said rail with said toothed segments; another lever-mechanism connecting the said rail with the abutment-carrying levers; lugs forming members of the counting-mechanism and a third lever-mechanism connecting the said rail with 10 these lugs; a hammer-mechanism and type hammers forming members of this mechanism, a common axle for said hammers; a rocking bar arranged transversely with respect to said type-hammers and being 15 adapted to release them; and means for transmitting motion from the machine shaft to said rocking bar.

4. A printing device for calculating machines, comprising, in combination a driving mechanism, a writing roller; type-bars adapted to be adjusted by means of said driving mechanism and being arranged in front of said roller; means for vertically guiding said bars; a counting mechanism 20 and cog-wheels forming members of this mechanism; toothed segments adapted to co-operate with said cog-wheels; a lever-mechanism adapted to couple said type-bars with said toothed segments; a hammer-mechanism and type hammers forming members of this mechanism; a common axle for said hammers; locking hooks for these latter; guide-levers hinged to these hooks; a common driving rod for these levers; and bell-crank levers adapted to be actuated by means 25 of said type-bars and to support said guide-levers, substantially as described.

5. A printing device for calculating machines, comprising, in combination a driving mechanism; a writing roller; type-bars adapted to be adjusted by means of said driving mechanism and being arranged in front of said roller; means for vertically guiding said bars; a counting mechanism 30 and cog-wheels forming members of this mechanism; toothed segments adapted to co-operate with said cog-wheels; a hammer-mechanism and type hammers forming members of this mechanism; a common axle for said hammers; locking hooks for these latter; guide-levers hinged to these hooks; a common driving rod for these levers; and bell-crank levers having each a downwardly 35 directed arm and a horizontal one with a double bend; projections at the downwardly directed arms of said bell-crank levers and engaging recesses of the said type-bars; and locking bars, of which each engages the two bends of one of the said bell-crank levers, substantially as described.

6. A printing device for calculating machines, comprising, in combination a driving mechanism; a writing roller; type-bars adapted to be adjusted by means of said driving mechanism and being arranged in front of said roller; means for vertically guiding said bars; a counting mechanism and cog-wheels forming members of this mechanism; toothed segments adapted to co-operate with said cog-wheels; a hammer-mechanism and type hammers forming members of this mechanism; a common axle for said hammers; locking hooks for these latter; guide-levers hinged to these hooks; a common driving rod for these levers; and bell-crank levers adapted to be switched by means of said type-bars and to support said guide-levers; combined locking levers so arranged as to be adapted to engage said bell-crank levers; and rolls adapted to actuate 85 said locking levers, substantially as described.

7. A printing device for calculating machines, comprising, in combination a driving mechanism; a writing roller; type-bars adapted to be adjusted by means of said driving mechanism and being arranged in front of said roller; and means for vertically guiding said bars; a counting mechanism and cog-wheels forming members of this 90 mechanism; toothed segments adapted to co-operate with said cog-wheels; a lever-mechanism adapted to couple said type-bars with said toothed segments; a hammer-mechanism and type hammers forming members of this 95 mechanism; a common axle for said hammers; locking hooks for these latter; guide-levers hinged to these hooks; pins secured to the type-bars and being adapted to release said guide-levers; and other levers 100 hinged to said latter levers and having their arms bear with their frontal ends against projections of those of the said guide-levers that advance at the left side, substantially as described.

8. A printing device for calculating machines, comprising, in combination a driving mechanism, a writing roller; type-bars adapted to be adjusted by means of said driving mechanism and being arranged in front of said roller; means for vertically guiding said bars; a counting mechanism and cog-wheels forming members of this mechanism; toothed segments adapted to co-operate with said cog-wheels; a lever-mechanism adapted to couple said type-bars with said toothed segments; a hammer-mechanism and type hammers forming members of this mechanism; a common axle for said hammers; locking hooks for these latter; guide-levers hinged to these hooks; pins secured to the type-bars and being adapted to release said guide-levers; other levers hinged to said latter levers and having their arms bear with their frontal ends against projections of 115

120

125

130

those of the said guide-levers that advance at the left side; and recessed rails located below said hinged levers and supporting them, substantially as described.

- 5 9. A printing device for calculating machines, comprising, in combination a driving mechanism, a writing roller; type-bars adapted to be adjusted by means of said driving mechanism and being arranged in 10 front of said roller; means for vertically guiding said bars; a counting mechanism and cog-wheels forming members of this mechanism; toothed segments adapted to co-operate with said cog-wheels; a lever-mechanism adapted to couple said type-bars with 15 said toothed segments; abutments forming members of the driving mechanism and being adapted to be adjusted from the keys of the machine; bell-crank levers having one

arm extending over the associate abutment; stepped sectors attached to these arms and being adapted to co-operate with said abutments; a driving crank and motion-transmitting connections between it and said bell-crank levers; a main-crank and another 25 lever-mechanism connecting it with the shaft of said driving crank; a releasing key, and a third lever-mechanism adapted to be switched by this key and to support the pivot of the before-mentioned lever-mechanism, substantially as described.

In testimony whereof I affix my signature in presence of two witnesses.
